UNITED STATES PATENT OFFICE

2,549,484

UNDERWATER GEAR UNIT FOR OUTBOARD MOTORS

Elmer C. Kiekhaefer, Cedarburg, Wis.

Application May 19, 1949, Serial No. 94,108

12 Claims. (Cl. 115—17)

1

This invention relates to the lower underwater gear case unit for outboard motors and particularly to the construction and assembly of the lower unit including the engine coolant pump, and is a continuation in part of the application of the present inventor filed May 12, 1947, Serial No. 747,443 for Outboard Motor.

The invention provides in either a conventional or a reversing lower unit, subassemblies of the parts of the unit on the respective drive and propeller shafts which are adapted to be disposed and mounted in and to close the respective recesses of the gear case and to include the water coolant circulating means for the motor.

A principal object of the invention is to provide for assembly of the lower unit and water pump of an outboard motor in a single piece gear case or housing.

Another object is to provide in a lower housing a pump unit therefor adapted to close the housing and to be removably disposed therein to register with the water coolant system of the motor.

Another object of the invention is to provide for the operation of the pump for circulating water to the engine at all times during the operation of the latter and to dispose the pump for assembly as a unit on the propeller shaft of the motor.

Another object is to provide for the inspection of the pump without disassembly of the other parts of the lower unit.

Another object is to reduce the number of seals required for the lower end assembly and unit.

These and other objects and advantages will be more fully set forth in the following description of a preferred embodiment of the invention as illustrated in the accompanying drawings.

In the drawings:

Figure 1 is a perspective view of the pump body comprising the closure member of the underwear housing and the disc which secures the pump body within the housing and completes the pump unit;

Fig. 2 is an elevation of an outboard motor including a lower underwear unit and pump unit shown in Fig. 1;

Fig. 3 is an enlarged longitudinal vertical section through the gear case housing of the outboard motor shown in Fig. 2;

Fig. 4 is a transverse section taken on line 4—4 of Fig. 3 through the pump unit;

Fig. 5 is a transverse section similar to Fig. 3 showing an alternate embodiment of the inven-

2

tion in a reverse gear housing for an outboard motor;

Fig. 6 is a transverse section taken on line 6—6 of Fig. 5 and showing the reverse gear control rod and connecting elements of the shifting mechanism in elevation and in relation to and projected upon the section;

Fig. 7 is a plan view of a gear housing showing the pump unit as disposed in the upper end of the housing and mounted on the drive shaft; and

Fig. 8 is a transverse vertical section of the lower unit shown in plan view in Fig. 7 and including a reverse gear assembly similar to that shown in Figs. 5 and 6.

The outboard motor shown in the drawings includes the engine 1 having a water coolant circulating system, not shown, the housing 2 supporting engine 1 at its upper end, the lower underwater propeller unit 3 carried by housing 2 at its lower end and the drive shaft 4 extending vertically within housing 2 to connect engine 1 and the propeller unit 3.

The cylindrical pump body or cartridge member 5 shown in Fig. 1 is provided with the inner chamber 6 of circular section formed eccentrically with respect to the axis of the pump body 5 and which opens endwise of body 5. The threaded disc 7 is adapted to be disposed, as will be described, to close chamber 6.

The lower unit 3 shown in Figs. 2, 3 and 4 is similar to that described and claimed in the above mentioned co-pending application of the present inventor and includes the gear housing 8 and the pump member 5 shown in Fig. 1.

Housing 8 comprises a single member which is preferably die cast and includes the cored vertical passage 9 opening at the planiform upper face 10 of the casting and communicating with the lower horizontal cored chamber 11 opening rearwardly of the casting.

The narrow forward or leading edge section 12 of housing 8 is straight throughout the height of the casting and merges into the forward edge of the lower skeg 13 integrally with the housing.

The enlarged torpedo section 14 projecting rearwardly of the housing 8 above skeg 13 is of circular section at its rear open end complementary to the forward end of the hub 15 of the propeller 16, and merges forwardly into the forward section 12 of the housing. The trailing edge 17 of the housing above torpedo section 14 is cut away as at 18 to receive a nut 19 for securing housings 8 and 2, as will be described.

Passage 9 is of sufficient size to receive drive shaft 4 while requiring a minimum transverse dimension or frontal area of that part of housing 8 above torpedo section 14, and immediately forwardly of the blades of propeller 16.

The shoulder 20 and the larger machined circular bore 21 is provided at the upper end of passage 9. Chamber 11 opening rearwardly of housing 8 is formed within the enlarged torpedo section 14 of housing 8 and is provided with a forward upper pocket 22 which communicates within the housing with the lower end of passage 9. The shoulder 23 and the larger circular bore 24 forming the rear portion of chamber 11 is machined after casting and threaded as at 25.

The upper end of drive shaft 4 is connected to the crankshaft, not shown, of engine 1 and extends downwardly through passage 9 into chamber 11 of gear housing 8. The ball bearing unit 26 is supported on shoulder 20 and carries shaft 4 in the upper machined end 21 of passage 9 and concentrically therewith. The roller bearing unit 27 is disposed in the lower end of passage 9 immediately above chamber 11 and carries the lower portion of shaft 4 which is of larger diameter to provide the shoulder 28 in engagement with bearing unit 26.

The beveled drive gear 29 disposed within pocket 22 of chamber 11 is mounted and secured on the lower splined end 30 of shaft 4 by the screw 31.

The roller bearing 32 mounted in the forward recess 33 of chamber 11 journal supports the forward end of the shaft 34 which extends through chamber 11 and rearwardly thereof to carry propeller 16. The driven gear 35 secured on shaft 34 by the pin 36 meshes with gear 29 and is carried by the ball bearing unit 37. Bearing 37 fits the machined bore 24 to support shaft 34 concentrically therewith and is disposed adjacent shoulder 23 to engage the same as will be described.

The stepped ring retainer 38 carrying the flange-type seal 39 is disposed in the upper end of bore 21 and projects above the upper face 10 of housing 8 to fit accurately the bore 40 in the lower end of housing 2 to align the housings upon assembly. Retainer 38 seated on bearing 26 and with seal 39 engaging shaft 4, closes passage 9 and secures bearing 26 against shoulder 20.

According to the invention, the cylindrical pump member or cartridge 5 including the outer ring seal 41 and the inner flange-type seal 42 engaging shaft 34 is disposed in bore 24 rearwardly of bearing 37 to close chamber 11.

In the assembly of lower unit 3 bearings 27 and 32 are first located in gear housing 8. Shaft 4 with bearing 26 mounted thereon may then be installed in passage 9 and thereafter gear 29 is secured thereon with screw 31 using chamber 11 for access to the lower end 30 of shaft 4.

The assembly comprising shaft 34, gear 35 secured thereon by pin 36, bearing 37 secured on the hub of gear 35 by means of the snap ring 43 and pump member 5 are then installed in chamber 11. The shims 44 are employed where necessary between shoulder 20 and bearing 26 and shoulder 23 and bearing 37 to dispose gears 29 and 35 in the correct relationship.

The forward tie-bolt 45 and the rear bolt 46 receiving nut 19 secure gear housing 8 to the lower end of drive shaft housing 2 with ring member 38 closing passage 9 seated in bore 40 in the lower end of housing 2 so that the vertical thrust

of gear 29 on shaft 4 is transmitted through bearing 26 and member 38 to housing 2.

The closure disc 7 fitting the threads 25 in the rear of chamber 11 and having a central hole 5 accommodating shaft 34 is disposed against pump member 5 and secures the same forwardly against bearing 37. The ring 47 disposed between bearing 37 and member 5 engages seal 41 to compress the same axially and to expand the same outwardly against the wall of chamber 11 in watertight engagement therewith. Disc 7 through member 5 further secures bearing 37 against shoulder 23 to maintain gear 25 in the predetermined desired position and receives the axial thrust of the gear in the operation of the motor. The forward thrust of propeller 16 is carried by bearing 37 through gear 35, pin 36 and snap ring 43.

The pump member 5 is disposed in chamber 11 so that the water inlet ports 48 in the side of torpedo section 14 of housing 8 register with the lower inlet 49 of pump housing 5 opening into chamber 6.

The discharge passage 50 in housing 8 may be formed by drilling the cast housing 8 from chamber 11 angularly into the lower end of the cored hole 51. The hole 51, as shown, receives the lower end of the water supply pipe 52 which latter is connected with the water circulating system, not shown, of engine 1 and communicates through passage 50 with the outlet 53 of pump housing 5.

The vane type impeller 54 is mounted on shaft 34 and rotationally secured thereto by the key 55 within chamber 6 of pump member 5 in the assembly of shaft 34 therewith as described above or otherwise prior to securing disc 7 in place at the opening of chamber 11. Chamber 6 is eccentrically disposed with respect to shaft 34 passing through housing 5 for operation of the pump by displacement or by centrifugal action to supply water through passage 50 and pipe 52 to the cooling system of engine 1 at all times while the motor is in operation. Pump member 5 is secured within chamber 11 against rotation by tightening disc 7. Disc 7, if threaded oppositely of the rotation of shaft 34, is adequately secured without other means.

In the lower end unit 56 shown in Figs. 5 and 6 of the drawings the gear housing 57 is provided with the chamber 58 opening rearwardly of housing 57 to receive the gears 59 and 60 which engage and are driven by drive gear 29 on shaft 4 in opposite directions.

The double row of bearings 37 mounted in the machined bore 61 of chamber 58 and carrying hub 62 of gear 59 rotatably supports gear 59 and with bearing 32 in the forward end of chamber 58 supports the propeller shaft 63 which is free to rotate in the bore 64 of hub 62 through which it extends rearwardly of housing 57.

Gear 60 is disposed forwardly of gear 29 and is carried by the rollers 65 on shaft 63 for free rotation with respect thereto. The axial thrust bearing washer 66 on shaft 62 is provided forwardly of gear 60.

The selective rotational driving connection of shaft 63 and gear 59 or 60 is provided by the clutch collar 67 mounted on shaft 63 for limited axial movement between the gears. The pin 68 carried by collar 67 projects through the slot 69 in shaft 63 to secure the latter and collar 67 rotationally.

The crank 70 is pivotally secured by the pin 71

within the slot 72 formed in housing 57 at the bottom of chamber 58 and includes the open yoke 73, the ends of which ride in the annular slot 74 of collar 67. The control rod 75 extending downwardly through housing 56 in the bore 76 is connected to crank 70 by the yoke 77 extending around the hub of gear 60. Movement of rod 75 as controlled by the operator of the outboard motor moves clutch collar 67 through crank 70 into or out of engagement with the clutch faces 78 of gear 59 or 60 whereby propeller 16 carried by shaft 63 is driven in a forward or rearward direction. In the position of collar 67 shown in Fig. 5 intermediate gears 59 and 60 shaft 63 is not driven in either direction so that the motor may be operated in "neutral."

As in the embodiment of the invention shown in Fig. 3, the threaded closure disc 7 installed near the rear opening of chamber 58 secures the pump member 5 and bearings 37 in chamber 58 against the shoulder 79 of housing 57.

Impeller 54 in chamber 6 of pump member 5 is mounted on hub 62 of gear 59 which extends rearwardly through member 5 and disc 7. The cap 80 mounted on the splines 81 of shaft 63 carries the flange-type seal 82 which closes the end of hub 62 to prevent water from passing between shaft 64 and the hub into chamber 58.

The assembly of drive shaft 4 and the driving gear 29 in chamber 58 of lower unit 56 is similar to that of lower unit 3 described above.

The control rod 75, crank 70 and yoke 73 are then assembled in housing 57 but without pin 71. The forward driven gear 60 with rollers 65 is then disposed in chamber 58 with the washer 66.

The assembly comprising shaft 63, gear 59, bearings 37 assembled on the hub 62 of gear 59 with snap ring 43, clutch collar 67, pump member 5 and impeller 54 mounted on hub 62 as described, is then installed in chamber 58.

The initial location of gear 60 may be established and maintained by interchanging washer 66 with washers of different thickness and shims 44 are employed to adjust the positions of gears 29 and 59.

The closure disc 7 having a slightly larger hole to accommodate hub 62 of gear 59 is then installed to close housing 57 and secure pump member 5 and bearings 37 against shoulder 79. Seal 62 is fitted with cap 80 on shaft 63 to complete the lower unit for receiving propeller 16.

In the lower end unit 83 shown in Figs. 7 and 8, the housing 84 is provided with the vertical cored recess 85 and the chamber 86 communicating with recess 85 and opening rearwardly of housing 84.

The double row of bearings 37 in the machined bore 87 of housing 84 carries gear 59 and shaft 63. The closure member 88 fitting bore 87 carries seals 41 and 42 to close chamber 86 and is secured by disc 7 in the chamber which serves to hold bearings 37 against the shoulder 89 in chamber 86. Gear 60 and the control mechanism including rod 75 are employed as in the embodiment of the invention illustrated in Figs. 5 and 6.

The vertical drive shaft 90 carries drive gear 29 at its lower end and is supported by roller bearing unit 27 near the lower end of recess 85 and the ball bearing unit 26 mounted in the smaller machined bore 91 near the upper end of recess 85. Pump member 5 is mounted on shaft 90 on bearing unit 26 in the larger machined bore 92 at the upper end of recess 85 so that its inlet 49 registers with the slots 93 in the upper

face 94 of housing 84, and which extend from either side of the housing into the forward portion of bore 92.

The drive shaft housing 95 carries unit 83 which is secured thereto by the bolts 45 and 46 with the gasket 96 disposed therebetween. Housing 95 is provided with the bore 97 in its lower end which is complementary to bore 92 to receive the upper projecting part of pump member 5. Housing 95 serves to close chamber 6 in which impeller 54 is operatively mounted on shaft 90.

The water supply pipe 52 carried by housing 95 registers with the discharge recess 98 in the upper face 94 of housing 84 which receives the water coolant discharge from the outlet 53 of pump housing member 5.

Housing member 5 carrying seals 41 and 42 closes the upper end of recess 85 and is secured therein by housing 95 and tie bolts 45 and 46 which also through member 5 serve to secure bearing unit 26 against the shoulder 98.

In the assembly of unit 83, drive shaft 90 is first installed in recess 85 and drive gear 29 secured thereto as in lower units 1 and 56. The propeller shaft 63 and assembly including drive gears 59 and 60 and closure member 88 is then installed as in lower unit 56 described above.

Bearing unit 26 and a shim 44 as required are then assembled on shaft 90 and disposed in recess 85 with pump member 5 immediately above bearing unit 26. After securing impeller 54 on shaft 90 within chamber 6 of pump housing member 5 the lower unit may be secured to housing 95 with pump member 5 being disposed in the bore 97 to be closed by housing 95 and to align housings 84 and 95.

In the embodiments described, the cylindrical pump cartridge member 5 carrying the seals 41 and 42 serves to close the recess or chamber in which the same is disposed and with disc 7 or housing 95, secures the adjacent bearings assembled and supporting the respective shaft in the corresponding recess or chamber.

Pump chamber 6 of housing member 5 is readily opened for inspection by removing disc 7 or upon disassembly of housings 84 and 95 and upon removal of impeller 54 member 5 may be withdrawn from the housing without disassembly of other parts of the lower end unit.

In units 56 and 83, the pump unit is disposed so as to be operative with the motor at all times irrespective of the selective gear transmission means between the drive shaft connected to the motor and the propeller shaft.

Various embodiments of the invention may be employed within the scope of the accompanying claims.

I claim:

1. An outboard motor underwater propeller unit, comprising a housing member having a streamlined outer body and a chamber therein including a cylindrical bore opening axially of said housing, a shaft journally supported within said chamber and projecting centrally and axially through said bore and from said housing, a cylindrical pump body member disposed within said bore independently of said shaft, means retained by said pump body member within said bore to seal the same and said chamber, and a water coolant circulating impeller mounted on said shaft to operate within said pump body member.

2. An outboard motor underwater propeller unit, comprising a housing member having a streamlined outer body and a chamber therein including a cylindrical bore opening axially of

said housing, a shaft journally supported within said chamber and projecting centrally and axially through said bore and from said housing, a cylindrical pump body member disposed within said bore independently of said shaft to seal the same and said chamber, said body member having a pump chamber formed therein opening exteriorly of the housing, an impeller mounted on said shaft to operate within said pump chamber, and a disc secured within said bore to said housing exteriorly of said pump body member and closing the latter and securing the same within said housing.

3. An outboard motor underwater propeller unit, comprising a housing member having a streamlined outer body and a chamber therein including a cylindrical bore opening axially of said housing, a shaft journally supported within said chamber and projecting centrally and axially through said bore and from said housing, a cylindrical pump body member disposed within said bore independently of said shaft to seal the same and said chamber, said body member having a pump chamber formed therein opening exteriorly of the housing, an impeller mounted on said shaft to operate within said pump chamber, and a member secured to said housing closing said pump chamber and retaining said cylindrical pump body member within said bore.

4. In an outboard motor, an underwater propeller unit comprising a cast housing member having a streamlined outer body and a chamber therein including a cylindrical bore opening, a bearing mounted within said bore opening of said housing, a shaft journally carried by said bearing and extending from within said chamber through said bore opening, a water coolant supply passage for said motor within the body of said cast housing member communicating with said bore exteriorly of said bearing, a cylindrical closure member mounted within said opening independently of said shaft and securing said bearing within said housing and closing said chamber, and a water coolant circulating pump impeller operatively mounted on said propeller shaft, said closure member comprising an outer body for said pump impeller and having an outlet communicating directly with said passage.

5. An outboard motor underwater propeller unit, comprising a housing member having a streamlined outer body and a chamber therein including a cylindrical bore opening longitudinally of said housing, said housing having adjacent to said chamber an annular shoulder formed by said bore and facing the open end thereof, a bearing disposed within the bore and against the shoulder of said housing, a shaft extending through the bore and into the chamber of said housing and journally carried by said bearing, said bearing also constituting an axial thrust bearing securing said shaft axially within said bore, a cylindrical pump body mounted within the bore of said housing and closing the same and said chamber and securing said bearing axially against the shoulder of said housing independently of said shaft, and a flexible vane pump impeller mounted on said shaft to operate within said pump body.

6. An outboard motor underwater propeller unit, comprising a housing member having a streamlined outer body and a chamber therein including a cylindrical bore opening longitudinally of said housing, said housing having within said chamber an annular shoulder formed by said bore and facing the open end thereof, a bearing

disposed within the bore and against the shoulder of said housing, a shaft extending through the bore and journally carried by said bearing, said bearing also constituting an axial thrust bearing securing said shaft axially within said bore, a cylindrical pump body mounted within the bore of said housing and closing the same and said chamber and securing said bearing axially against the shoulder of said housing independently of said shaft, said pump body having a chamber formed therein and opening exteriorly, a pump impeller mounted on said shaft to operate within said last named chamber, and a disc threadedly secured within the bore of said housing and exteriorly of said pump body to close the latter and securing the same therein and said bearing against the shoulder thereof and said shaft against axial displacement.

7. An outboard motor underwater propeller unit, comprising a housing member having a streamlined outer body and a chamber therein including a cylindrical bore opening longitudinally of said housing, said housing having within said chamber an annular shoulder formed by said bore and facing the open end thereof, a bearing disposed within the bore and against the shoulder of said housing, a shaft extending through the bore and journally carried by said bearing, said bearing also constituting an axial thrust bearing securing said shaft axially within said bore, a cylindrical pump body mounted within the bore of said housing and closing the same and said chamber and securing said bearing axially against the shoulder of said housing independently of said shaft, said pump body having a chamber formed therein and opening exteriorly, a pump impeller mounted on said shaft to operate within said last named chamber, and means closing said pump body and securing the same within said housing and said bearing against the shoulder thereof and said shaft against axial displacement.

8. An outboard motor underwater assembly, comprising a single piece cast metal housing having a gear chamber therein with an upwardly opening bore to receive the drive shaft and a rearwardly opening bore to receive the propeller shaft, said housing having an outwardly facing circumferential shoulder adjacent said gear chamber and at the inner end of each of said bores, a drive shaft in said upwardly opening bore and having a drive gear secured thereon in said gear chamber, a propeller shaft centrally of said rearwardly opening bore and extending into said gear chamber and having thereon a driven gear meshing with said drive gear, a bearing disposed in each bore to support each corresponding shaft and gear for rotation, means securing each said bearing against the corresponding shoulder to secure said bearings and corresponding shafts against axial displacement in either direction, one of said last named means comprising a cylindrical pump unit mounted for free axial adjustment upon the corresponding shaft and secured in the corresponding bore against the bearing, said housing having a passage extending from the pump and continuously to the upper end of said housing to receive water discharged by the pump and a second passage through the wall of the bore adjacent said pump to supply water to the pump, a seal ring disposed between said pump and the adjacent bearing and expanded into sealing engagement with the wall of the corresponding bore inwardly of said passages to seal said gear chamber from

leakage of water into the same, and means sealing said pump unit upon said shaft to complete the sealing of said chamber.

9. The structure of claim 8 in which the pump unit comprises a pump casing disposed independently of the shaft therethrough and carrying the shaft seal, and a flexible vane impeller mounted upon the shaft and disposed for rotation within the pump casing.

10. The structure of claim 8 in which the pump unit comprises a casing opening outwardly of the housing and carrying the shaft seal, a rotary impeller mounted upon the shaft for rotation within said casing, and a plate closing the pump casing and removably secured within the corresponding bore of the housing.

11. An outboard motor underwater assembly, comprising a single piece cast metal streamlined housing free of parting lines exposed to the water in which it is submerged and having a gear chamber therein with a rearwardly opening bore to receive the propeller shaft, said housing having an outwardly facing circumferential shoulder adjacent the gear chamber and at the inner end of the bore and having a water inlet passage through the wall of said bore and spaced rearwardly of said shoulder and a water coolant passage extending from said bore at a location spaced rearwardly of said shoulder to the top of said housing, a propeller shaft disposed centrally of said bore, a combined journal and axial thrust bearing disposed in said bore and against said shoulder to rotationally support said shaft, a pump cartridge mounted for free axial adjust-

ment upon said shaft and secured within said bore and against said bearing to thereby secure said shaft against axial displacement in either direction, said pump cartridge having a radially disposed inlet registering with said inlet passage in said housing wall and a radially disposed discharge outlet registering with said water coolant passage in said housing, and means sealing said pump cartridge to the shaft and to the walls of said bore at a location between said bearing and said inlet and outlet passages to close said bore against leakage of water into said gear chamber.

12. The structure of claim 11 in which the pump cartridge is secured within the bore of the housing by means threaded in the outer end of said bore.
